LADY'S STOCKING

Leonard J. Accardi, Jamaica, N. Y.

Application November 16, 1954, Serial No. 33,113

Term of patent 7 years

(Cl. D47—7)

Fig. 1 is a side elevational view of a lady's stocking embodying my new design; and

Fig. 2 is an enlarged perspective view of a portion of the lady's stocking shown in Fig. 1 embodying my new design.

I claim:

The ornamental design for a lady's stocking, as shown.
